US0D1040006S

(12) **United States Design Patent** (10) **Patent No.:** **US D1,040,006 S**
Feng (45) **Date of Patent:** **** Aug. 27, 2024**

(54) **BAND**

(71) Applicant: **Shenzhen Zhixing Sichuang Technology Co., Ltd.**, Guangdong (CN)

(72) Inventor: **Hai Jun Feng**, Guangdong (CN)

(**) Term: **15 Years**

(21) Appl. No.: **29/896,845**

(22) Filed: **Jul. 7, 2023**

(51) LOC (14) Cl. **11-01**

(52) U.S. Cl.

USPC **D11/3**

(58) **Field of Classification Search**

USPC D11/1-6; D10/32

CPC A44C 5/00-003; A44C 5/24

See application file for complete search history.

(57) **CLAIM**

The ornamental design for a band, as shown and described.

DESCRIPTION

FIG. 1 is a perspective view of the band showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view of thereof;

FIG. 8 is a bottom plan view of thereof; and,

FIG. 9 is a perspective view thereof when it is being used. The straight broken lines on the band show stitch lines that form part of the claimed design. The broken lines showing features on the connectors illustrate portions of the article that form no part of the claimed design. The broken lines showing the watch face in FIG. 9 illustrate environment and form no part of the claimed design.

1 Claim, 9 Drawing Sheets
